(57) **CLAIM**

The ornamental design for a holder for a dual screen communication device, as shown and described.

DESCRIPTION

FIG. 1 is a front perspective view of a holder for a dual screen communication device.

FIG. 2 is a rear perspective view of the holder for the dual screen communication device in use.

FIG. 3 is a side perspective view of the holder for the dual screen communication device in use.

FIG. 4 is a top plan view of the holder for the dual screen communication device in use.

FIG. 5 is a bottom plan view of the holder for the dual screen communication device in use.

FIG. 6 is a left elevation view of the holder for the dual screen communication device in use.

FIG. 7 is a right side view of the holder for the dual screen communication device in use.

FIG. 8 is a front plan view of the holder for the dual screen communication device in use; and,

FIG. 9 is a rear plan view of the holder for the dual screen communication device in use.

The broken lines in the various views depict a dual screen communication device showing the environment and forming no part of the claimed design.
